(57) **CLAIM**

The ornamental design for a reusable incontinence device applicator, as shown and described.

DESCRIPTION

FIG. 1 is an exploded perspective view showing the new design of the reusable incontinence device applicator, show-

ing an advancer used to insert an incontinence device (at a top of FIG. 1) and a body used to hold an incontinence device (at a bottom of FIG. 1).

FIG. 2 is an assembled perspective view of the reusable incontinence device applicator, showing the advancer in the body in an extended position.

FIG. 3 is an assembled perspective view of the reusable incontinence device applicator, showing the advancer in the body in a fully advanced position.

FIG. 4 is a perspective view of the body of the reusable incontinence device applicator.

FIG. 5 is a front view of the body of the reusable incontinence device applicator.

FIG. 6 is a rear view of the body of the reusable incontinence device applicator.

FIG. 7 is a top view of the body of the reusable incontinence device applicator.

FIG. 8 is a bottom view of the body of the reusable incontinence device applicator.

FIG. 9 is a right side view of the body of the reusable incontinence device applicator.

FIG. 10 is a left side view of the body of the reusable incontinence device applicator.

FIG. 11 is a perspective view of the advancer of the reusable incontinence device applicator.

FIG. 12 is a front view of the advancer of the reusable incontinence device applicator.

FIG. 13 is a rear view of the advancer of the reusable incontinence device applicator.

FIG. 14 is a top view of the advancer of the reusable incontinence device applicator.

FIG. 15 is a bottom view of the advancer of the reusable incontinence device applicator.

FIG. 16 is a right side view of the advancer of the reusable incontinence device applicator; and,

FIG. 17 is a left side view of the advancer of the reusable incontinence device applicator.
